UNITED STATES PATENT OFFICE.

WILLIAM F. MOULTON, OF BURLINGTON, VERMONT.

IMPROVEMENT IN EAVES-TROUGHS.

Specification forming part of Letters Patent No. 174,281, dated February 29, 1876; application filed August 14, 1875.

To all whom it may concern:

Be it known that I, WILLIAM F. MOULTON, of Burlington, in the county of Chittenden and in the State of Vermont, have invented certain new and useful Improvements in Wooden Eaves-Troughs and metallic flanged couplings; and do hereby declare that the following is a full, clear, and exact description thereof, reference being had to the accompanying drawings, and to the letters of reference marked thereon, making a part of this specification.

The nature of my invention consists in the construction and arrangement of a wooden eaves-trough with metallic couplings, as will be hereinafter more fully set forth.

In order to enable others skilled in the art to which my invention appertains to make and use the same, I will now proceed to describe its construction and operation, referring to the annexed drawing, in which—

Figure 1 is a perspective view of my invention. Fig. 2 represents the coupling, Figs. 3, 4, and 5 show the spout, and Fig. 6 is a transverse section of the eaves-trough.

A represents a section of the wooden eaves-trough, having its exterior side made on a true circle, and the trough is turned, as shown in Fig. 6, so as to have an increased swell from the edges *x x* to the center *y*.

By this construction the center or bottom of the trough is by far the strongest point in the trough. This is necessary as the water when congealed expands, and if not firmly held will split the trough in the center, as that point is strained most by the two edges being lifted upon by the ice.

The edges *x x* of the trough are molded or rounded, giving the trough a neat and finished appearance. The outside being on a true circle also gives a good finish, and is easy to fit a hook to, which makes it better adapted to the wants of the public.

Each end of the trough-section A is cut down to form a tenon, B, of the same form as the trough. C represents the coupling made of metal to fit over the tenons of two adjoining sections. This coupling is made tapering from the cen-

ter toward both ends, and has a curved flange, *a*, along each edge to fit over the edges of the tenons. At the corners an angular connection or coupling, D, is used, as shown in Fig. 1, said coupling being also provided with flanges *a* for the insertion of the tenons of the trough-sections.

The tapering interior of the couplings makes a nice-fitting, strong, and durable joint when the correspondingly-shaped tenons are driven into the same.

As a connection from the trough to the spout or conductor, I use a T-shaped coupling, E, with an obtuse angle, G, made either in one piece, as shown in Fig. 4, or in two pieces, as shown in Figs. 3 and 5. By the use of this connection the hole in the trough may be bored at any given point, and the coupling nailed or screwed on the outside.

At the end of the trough is a flanged head, H, driven onto a shorter tenon formed on the trough.

Having thus fully described my invention, what I claim as new, and desire to secure by Letters Patent, is—

1. The wooden trough A formed with a true outside circle, its edges *x x* rounded or molded, and an increased swell from the edges to the center, substantially as and for the purposes herein set forth.

2. The coupling C formed tapering from the center toward both ends, and provided with flanges *a a* along its edges, substantially as and for the purposes herein set forth.

3. The coupling E G provided with the coupling-flange attached to the part E, and made tapering from the angle toward both ends, as set forth.

4. The flanged head H, in combination with the wooden trough A, for the purposes set forth.

In testimony that I claim the foregoing I have hereunto set my hand this 23d day of June, 1875.

W. F. MOULTON.
